(57) **CLAIM**

The ornamental design for the electrical circuit breaker charge cam, as shown.

DESCRIPTION

FIG. 1 is a perspective view of my new design for an electrical circuit breaker charge cam;

FIG. 2 is a perspective view of my new design for an electrical circuit breaker charge cam;

FIG. 3 is a front view thereof;

FIG. 4 is a right-side view thereof;

FIG. 5 is a left-side view thereof;

FIG. 6 is a back view thereof; and,

FIG. 7 is a top view thereof.
